CLAIM

The ornamental design for a camera, as shown and described.

DESCRIPTION

FIG. 1 is a top front left perspective view of a camera in accordance with our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a top front left perspective view of another embodiment of a camera in accordance with our new design;

FIG. 9 is a front elevation view thereof;

FIG. 10 is a rear elevation view thereof;

FIG. 11 is a top plan view thereof;

FIG. 12 is a bottom plan view thereof;

FIG. 13 is a left side elevation view thereof; and,

FIG. 14 is a right side elevation view thereof.

The broken lines in the Figures indicate environmental structure or boundaries of elements that form no part of the claimed design.
